UNITED STATES PATENT OFFICE.

EMIL ERICKSSON, OF CHICAGO, ILLINOIS, ASSIGNOR TO WM. A. FIELD COMPANY, OF CHICAGO, ILLINOIS, A CORPORATION OF ILLINOIS.

MACHINE FOR CORRECTING PRINTING PLATES.

Application filed December 12, 1923. Serial No. 680,187.

To all whom it may concern:

Be it known that I, EMIL ERICKSSON, a citizen of the United States, residing at Chicago, in the county of Cook and State of Illinois, have invented certain new and useful Improvements in Machines for Correcting Printing Plates, of which the following is a specification.

The machine of the present invention is in the form of a press designed for the purpose of correcting inequalities appearing in the type surface of a printing plate prior to the setting up of the plate in a printing press. Printing plates, after casting and before correction, are ordinarily found to present inequalities in the type surface due to warping of the metal or similar causes, so that the type surface does not present a true plane, with the result that if a plate of this character be set up in a printing press in uncorrected condition, it will not register a true impression on the paper. In order to correct such an imperfect plate, it becomes necessary to apply pressure in such a manner as to transfer inequalities of the type surface to the back of the plate by pressing or leveling out the type surface, by maintaining the type surface under pressure against a plain unyielding bed or plate, and by providing means acting against the back of the plate in such a way as to permit the inequalities to register in the back rather than in the type surface.

The present invention relates to a press of a character which is designed to correct the plates prior to their introduction into the printing press which permits a large number of plates to be corrected in rapid succession, and thereafter distributed for use on various printing presses.

The invention consists in the features of construction and combinations of parts hereinafter described and claimed.

In the drawings:

Figure 1 is a front elevation of the machine of the present invention;

Fig. 2 is a section taken on line 2—2 of Fig. 1;

Fig. 3 is a section taken on line 3—3 of Fig. 1;

Fig. 4 is an enlarged detail showing one of the removable face plates which furnishes the upper contact surface for the type plate under correction;

Fig. 5 is a plan view partly broken away,

showing means for effecting in and out reciprocation of one of the supporting plates;

Fig. 6 is a view taken on line 6—6 of Fig. 5;

Fig. 7 is a sectional view taken at right angles to the above on line 7—7 of Fig. 5;

Fig. 8 is a sectional detail showing a printing plate in position prior to correction with inequalities in its upper face; and

Fig. 9 is a similar view showing the same plate after correction with the inequalities transferred to the back surface.

The machine, as a whole, is mounted upon a base 10 provided with two sets of standards 11 and 12 respectively, the standards 11 comprising the right hand set being six in number, and the standards 12 comprising the left hand set being four in number. All the standards extend in vertical relation to the base and in parallel relation to one another and furnish guideways for the vertical reciprocation of a right hand press head 13 and a left hand press head 14 which are adapted to be raised and lowered by suitable hydraulic or other means which need not be described in detail.

The right hand press 13 is provided at its corners with guide lugs 15 which embrace the proximate corner standards 11, and at intermediate points with guide lugs 16 which embrace the intermediate standards 11 and slide freely thereon as the press head is raised and lowered. Similarly the press head 14 is provided with corner guide lugs 17 four in number, which embrace the proximate standards 12. The press head 13 is provided on its top with a sliding table plate 18 which is guided between flanges 19 for in and out reciprocation; and the press head 14 is provided with a similar table plate 20 guided by flanges 21 and likewise adapted to be moved in and out. Interposed between the two tables and in contact with the adjacent guide flanges 19 and 21 is a bridge plate 22, the inner edge of which abuts against the adjacent inner front standards 11 and 12 and extends forwardly therefrom, which bridge plate is loosely laid against the flanges 19 and 22, so that either of the press heads may be lifted slightly and thereby tilt the abutting edge of the bridge plate without displacing the bridge plate from its position intermediate the two press heads.

As shown in Figs. 1 and 2, the flanges 110

19 and 21 extend upwardly from two pairs of supporting guide rails 23 which serve to support the bridge plate 22 in constantly projected position and also serve as guides 5 for the in and out reciprocations of the two table plates. The guide rails project a considerable distance forwardly from the body of the machine and extend from front to rear thereof in parallel relation to afford 10 the necessary movements.

Each of the tables is provided with means for effecting in and out reciprocation thereof, which means, in each instance, are the same, so that a description of one will serve 15 for both. Each of the press heads has secured to its front side a bracket casting 24 provided with supporting arms 25 which extend laterally to and are integrally formed with the guide rails 23. The arms and the 20 bracket casting merge into a top plate 26 which bridges the space between the guide rails 23 and furnishes a rugged support for the operating mechanism housed below each 25 of the slidable table plates. Each table is provided near its front edge with a pair of spaced guide bars 27 which afford a guide channel for the reception of a roller 28 which is carried at the front end of a swinging arm 29 mounted at the upper end of a vertical stub shaft 30 which passes through 30 a bearing sleeve 31 forming part of the bracket casting. The arrangement is such that as the stub shaft is rotated in either direction the roller 28 riding within the 35 guide channel will move the table back and forth to the desired degree.

The stub shaft 31 has mounted thereon a worm gear 32 which is adapted to receive motion from a worm 33 carried by a shaft 34, which latter is journaled within a swinging bracket 35. The shaft carries a spur gear 36 which meshes with a spur gear 37 on a constantly rotating shaft 38 upon which the swinging bracket 35 is loosely mounted, 40 so that the bracket may be swung back and forth without unmeshing the gears. When the bracket is swung forwardly by bearing down upon a pivoted lever arm 39, it will bring the worm 33 into mesh with the worm gear 32 and the latter will begin to rotate. The upper end of the bracket 35 is provided with a lug 40 which is adapted to engage with a notch 41 in a dog 42 pivoted at its forward end to a pin 43 and provided 45 at its intermediate point with a notch 44. The notch 44 is adapted to occupy a position within the line of movement of either one of two lugs 45 upstanding from the upper face of the worm gear 32. The arrangement is such that when the bracket 35 is swung upwardly by the depression of the lever arm 39, the lug 40 will be engaged by the notch 41 in the dog, holding the 50 parts in latched relation during a half rotation of the worm gear 32, at which 55 time

one of the lugs 45 will have reached a position where it will ride under the notch 44 in the dog, and by engaging the beveled forward end of the notch lift the dog, thereby disengaging the notch 41 from the lug 40 and permitting the bracket 35 to swing back, unmeshing the transmission train, and stopping further movement of the table. This will impart a half rotation to the arm 29 which will serve to swing the arm from 75 its extreme forward medial position to its extreme rearward medial position, or vice versa, as the case may be, thereby imparting either an in movement or an out movement to the table plate, depending upon the 80 position originally occupied.

The press head 13 with its table plate 18 co-acts with a fixedly mounted upper press head 46 provided with a removable face plate 47, which latter is preferably 85 made of hardened steel and constitutes the plane surface against which the type surface of the type plate is corrected. The edges of the face plate engage undercut guide flanges 48 and the plate is provided with 90 a handle 49 permitting its removal for the purpose of cleaning from time to time. The left hand press head 14 and table plate 20 co-act with a fixed upper press head 50 which is provided with a removable face 95 plate 51 similar in all respects to that previously described and slidably mounted between undercut guide flanges 52. The two press heads are fixedly mounted upon the upper ends of the standards 11 and 12 respectively; and the right hand fixed press head is bored to receive a plurality of gas burners 53, the gas nozzles of which project downwardly so as to heat the surface of the face plate 48 which contacts the type plate 100 under correction.

Suitable gas pipe connections are provided for the gas nozzles, but these need not be described in detail. The gas burners 53 connect with a header pipe 54 shown in Fig. 2. The fixed press head 50 is provided with a chamber 50^a having entered thereinto an inflow pipe 55 and an outflow pipe 56 adapted to furnish a supply of cold water to the chamber for the purpose of cooling the 110 chamber, the right hand press heads serving to correct the printing plates under heat, and the left hand chamber serving thereafter to cool them before removal from the 115 machine.

The shaft 38 is provided with universal connections 57 which accommodate the up and down movements of the respective presses. The shaft is operated from any suitable source of power, as, for instance, a 125 motor 59. Suitable means for operating either of the hydraulic mechanisms are also provided.

Each table plate is provided with an embossed correction backing for the printing 130

plate, which backing is shown in detail in Figs. 8 and 9, although the precise form of backing may be varied or modified, it being understood that the form here shown serves 5 merely for purposes of illustration, and that other forms having similar capacities may be used in lieu thereof. As shown, the correction backing consists of a base layer 60 having formed thereon spaced bosses or protuberances 61 of some yieldable material or composition overlaid with a facing layer 62. The bosses or protuberances are adapted to yield locally when pressure is applied to correct the printing plate, and being spaced 10 apart from one another are adapted to distort locally to the degree required to accommodate varying inequalities in the thickness of the plate.

The correction backing may be afforded 20 either by a material having elastic properties like rubber which will tend to restore to normal condition after distortion, in which case the same correction backing can be used permanently in the press without frequent renewal; or the backing may be formed of such a composition as will crush down and deform under pressure after a single plate has been corrected, in which case the correction backing will be in the form of 30 removable sheets or layers adapted for frequent substitution.

The correction layer in whatsoever form, however, has the capacity for local distortion, either temporary or permanent, and 35 should preferably provide displacement gaps or spaces to accommodate the local deformation due to transference, under compression, of inequalities in the type surface to the back surface, as indicated in Figs. 8 and 9. In 40 use, the mechanisms which control the right and left table plates are operated to bring both of the tables into projected position, and the correction backing layer is positioned in place on the right hand table, with 45 the type plate resting thereon faced upward. The press head being in lowered position, as soon as the printing plate is positioned, the mechanism for controlling the right hand table plate is operated and the table plate will be moved back into position to 50 bring the type surface immediately below the heated face plate of the right hand press. Thereupon, the right hand hydraulic or other pressure mechanism will be actuated 55 and the right hand press head lifted to bring the type surface into contact with the heated plate. After the type plate has been heated sufficiently to render it slightly plastic, the pressure is increased to the amount 60 required to level out the type surface and press down the inequalities therein, which inequalities will then appear upon the back surface of the type plate and will cause varying indentations in the correction backing layer, as indicated in Figs. 8 and 9, the

backing layer deforming or displacing in varying amount to accommodate the inequalities.

After the plate has been corrected, the press head is lowered, and the right hand table restored to its initial position which brings the two table plates and the intervening bridge plate into plane alignment, so that the corrected plate still mounted upon the correction backing may be slid over onto 70 the left hand table plate which is then actuated to bring the type plate with its backing into interposed relation to the press heads of the left hand press, after which the left hand press head is raised and the type plate maintained in contact with the cool surface of the left hand upper press plate for a sufficient time to cool the type plate, after which the left hand table is restored which completes 75 the operation. In manipulating the type plate, it is not always necessary to move the back correction layer with the type plate since, if desired, each of the table plates may be provided with a permanently attached correction back layer having a yielding surface, in which case the type plate is simply moved across from one to the other.

Although the invention has been described with particularity, it is not the intention to limit the invention to the precise details shown and described, since, as previously indicated, the formation of the correction backing layer or other features of the press structure may be modified without departing 95 from the spirit of the invention.

I claim:

1. In a machine for correcting printing plates, the combination of two presses each provided with a fixed upper press head and a movable lower press head, independent means for actuating each of the lower press heads, a table plate carried by each of the lower press heads, guide mountings for each of said table plates for permitting movements thereof into and out of register with the co-operating fixed press head, a bridge plate located between the table plates, said table plates and said bridge plate lying in a continuous plane when both of said table plates are projected and lowered, means for heating one of the fixed press heads, and means for cooling the other fixed press head, substantially as described.

2. In a machine for correcting printing plates, the combination of two presses each provided with a fixed upper press head and a movable lower press head, independent means for actuating each of the lower press heads, a table plate carried by each of the lower press heads, guide mountings for each of said table plates for permitting movements thereof into and out of register with the co-operating fixed press head, a bridge plate located between the table plates, said

- table plates and said bridge plate lying in a continuous plane when both of said table plates are projected and lowered, means for heating one of the fixed press heads, means for cooling the other fixed press head, and a removable face plate for each of the fixed press heads, substantially as described.
3. In a machine for correcting printing plates, the combination of two presses each provided with a fixed upper press head and a movable lower press head, independent means for actuating each of the lower press heads, a table plate carried by each of the lower press heads, guide mountings for each of said table plates for permitting movements thereof into and out of register with the co-operating fixed press head, a bridge plate located between the table plates, said table plates and said bridge plate lying in a continuous plane when both of said table plates are projected and lowered, means for heating one of the fixed press heads, means for cooling the other fixed press head, and a correction backing layer mounted upon one of the tables and formed of material adapted to yield locally to inequalities in the surface of the printing plate being corrected, substantially as described.
4. In a machine for correcting printing plates, the combination of two presses each provided with a fixed upper press and a movable lower press head, independent means for actuating each of the lower press heads, a table plate carried by each of the lower press heads, guide mountings for each of said table plates for permitting movements thereof into and out of register with the co-operating fixed press head, a

bridge plate located between the table plates, said table plates and said bridge plate lying in a continuous plane when both of said table plates are projected and lowered, means for heating one of the fixed press heads, means for cooling the other fixed press head, a removable face plate for each of the fixed press heads, and a correction backing layer mounted upon one of the tables and formed of material adapted to yield locally to inequalities in the surface of the printing plate being corrected, substantially as described.

5. In a machine for correcting printing plate, the combination of two presses each provided with a fixed upper press head and a movable lower press head, independent means for actuating each of the lower press heads, a table plate carried by each of the lower press heads, guide mountings for each of said table plates for permitting movements thereof into and out of register with the co-acting fixed press head, a bridge plate located between the table plates, said table plates and said bridge plate lying in a continuous plane when both of said table plates are projected and lowered, means for heating one of the fixed press heads, means for cooling the other fixed press head, and a correction backing layer carried by one of the table plates and formed of yieldable material configured to present a surface consisting of bosses and intervening spaces to provide for the variable displacement of the bosses during the correction process, substantially as described.

EMIL ERICKSSON.
